LOOM STOP MOTION

Maurice R. Flamand, Central Falls, R. I., assignor to Draper Corporation, Hopedale, Mass., a corporation of Maine

Application August 28, 1953, Serial No. 377,013

11 Claims. (Cl. 139—354)

This invention pertains to a stop motion for use with looms of the type in which a twisted selvage is applied at least one part of the fabric being woven, said stop motion being effective upon failure of the selvage threads employed for that purpose.

It is a general object of the invention to devise a stop motion means of simple nature which shall function effectively upon each and all of the selvage threads employed in making a so-called twisted or Leno selvage and which preferably, shall function through one of the conventional stopping means such as a warp stop motion already to be found on such looms.

It is a more specific object of the invention to devise simple stopping means which shall, in effect, comprise a part of the shedding means for these selvage threads and which shall not be affected by either the shedding or twisting movement of the parts or threads and which may function upon failure of one of the threads or upon a thread becoming unduly slack to set in motion stopping mechanism for bringing the loom to rest very rapidly and before the continued weaving of any appreciable amount of fabric without a selvage.

It is a further object of the invention to devise a selvage thread stop motion which shall also serve to control or influence tension in the twisting or Leno threads thereby to improve the quality of the selvage.

Other objects of the invention will become apparent from the following more detailed disclosure.

In certain types of looms a natural selvage is not readily formed and in such looms, projecting weft threads are interlocked or a sort of selvage is formed by separately shedding a pair of selvage threads and by twisting them or imparting to them something in the nature of a Leno movement between each shedding motion. It has, in many instances, been the practice to run such looms without any stop motion for these selvage threads in which event the loom operator has had to pay rather close attention to each loom in order to prevent weaving of fabric for any appreciable period of time without the blocking of the projecting weft threads, that is, without forming a selvage at that side of the fabric at which a selvage thread has failed. In some instances the selvage threads have been passed through the regular warp stop motions and drop wires applied thereto in a manner to stop the loom in the event one of the threads has failed, but that requires positioning the supply of selvage threads which is preferably to be rotated, adjacent the rearmost portion of the loom and at a considerable distance from the shedding and twisting means therefor, that complicating the mechanism, making it rather ungainly in its appearance and design and in other ways being generally unacceptable.

According to the instant invention, a stop motion effective upon the failure of any one of the selvage threads serves to function, preferably through the regular warp stop motion, to stop the loom and this mechanism actually forms a part of a rotating disk structure for shedding and twisting the selvage threads thereby adding little

2

to the complication or bulk of the already existing mechanism. According to the invention, the intermittently rotating means by which the selvage threads are shed and by which they are twisted between each shedding movement is provided with a spring biased arm, one for each of the threads, which has its free end formed as an eyelet for the threading therethrough of the selvage thread individual thereto. During normal operation of the mechanism the tension in the selvage threads is sufficient to maintain these arms drawn inwardly so they are ineffective to stop the loom, but upon failure of a selvage thread or undue slackness therein, the spring arm or spring biased arm is adapted to move outwardly or to a position more radially directed relative to the disk to project beyond the outer periphery thereof for engagement with a contact member thereby to complete an electric circuit. Such circuit completion is preferably accomplished by grounding through the spring biased arm and thence through the associated parts and frame of the loom.

The arms, especially one form thereof, are adapted to tension the selvage threads continuously so that they interlock the projecting filling under more uniform conditions.

The invention will be described in greater detail by reference to the accompanying figures of drawing wherein:

Fig. 1 is a plan view of a selvage thread shedding and twisting mechanism to which the invention has been applied.

Fig. 2 is a diagrammatic view showing the general arrangement of the parts for manipulating the selvage threads, the stop motion and its relationship to the warp stop motion and other parts of the loom.

Fig. 3 is a detail view to a larger scale showing the general arrangement of certain of the parts of the mechanism.

Fig. 4 is a plan view somewhat similar to Fig. 1 showing a modification.

Fig. 5 is a diagrammatic view of this modified form.

Fig. 6 is a view similar to Fig. 3, but of the modification.

Fig. 7 is a wiring diagram showing one type of stop motion with which the invention may function.

Figs. 8 and 9 are detail views showing a modification of a part of the mechanism which pertains to making electrical contact at the warp stop motion.

Now referring to Figs. 1, 2 and 3, the invention applies to a selvage thread feeding and twisting means which comprises a rotating disk 10 mounted on a spindle 11 and being driven intermittently by certain gearing and intermittent drive means such as a Geneva movement, preferably enclosed within a casing 12. Rotating with disk 10, but preferably at a uniform speed, is a selvage thread supply means including disk 13, thread supplies 14 and 15 from which the selvage threads S are conducted first through the hollow interior of a spindle on which is mounted the disk 13, then through a similar hollow interior portion of the intermittently moving spindle 11. So much of the mechanism is well known and it is not necessary to describe the same here in greater detail. The supply spools 14 and 15 are suitably retarded so that they may not overrun and furthermore, tensioning means may be employed on the threads as they are drawn from these supply spools.

As more clearly illustrated in Fig. 2, the selvage thread feeding and twisting means is preferably located at the rear of the normal shedding mechanism for the warp threads, but forwardly of the warp beam and of the warp stop motion generally indicated by numerals 16 and 17. The warp threads are drawn over the usual whip roll 18 and then passed through suitable drop

wires 19, there being a plurality of banks of these wires, and then through the usual harness mechanism and reed 20, whereafter they are interlaced with filling threads to form a fabric F which is taken up in a cloth roll 21 as is the usual practice.

The disk 10 has mounted at either side of the spindle 11 on pivot screws 22 and 23, spring urged arms 24 and 25 having loops or eyelets of any suitable nature at or adjacent their ends through which the threads S are threaded after they emerge from the hub portion 26 of 10 the disk, and are passed through loops or eyelets 27 and 28. After being threaded through the loops at the arm ends, they are passed through the feeding apertures or eyelets 29 and 30 formed in the disk itself. From these last mentioned eyelets the selvage threads S pass onwardly to be threaded through certain dents of the reed 29 and cross at the fell of the forming fabric being shed due to the intermittent rotary movement of disk 10 which is timed to make one-half revolution every two picks according to a preferred selvage construction, although a 20 change may be effected at each pick or each time the harnesses change, the effect of this intermittent feeding disk on the threads being such as to twist them each time a half revolution is effected. That binds in the end of filling and since the threads S are under suitable tension, 25 a relatively tight and effective selvage is produced.

Now referring to Fig. 3, the pivot for one of the arms such as the arm 24 is shown in detail. The pivot screw 22 is threaded into the disk 10 which has a counterbored boss or hub 31 against the outer face of which the hub portion of the arm is adapted to bear and within which a spring 32 is fixed at one end in the disk and at its other end in the arm. This spring is under suitable tension to urge the arm in a direction outwardly or radially of the disk. Normally the tension under which the selvage 30 threads S are drawn from their supplies is such that the arms will be held inwardly or adjacent the loops 27 and 28 so that the free ends of the arms may not project beyond the periphery of the disk. However, upon failure of one of the threads either due to a break or to loss of tension, the spring becomes effective for moving that arm outwardly to the dot-and-dash line position of Fig. 2, in which position it extends beyond the periphery of the disk 10 and is adapted to contact a rod 33 which is held at end support 34 and which is in turn electrically connected to one or more of the electrodes 35, one of each being evident at each bank of the warp stop motion. The rod 33 is insulated from the holder in which it is fixed, but connects by a lead 36 to a contacting clamp 37 at the electrodes of the stop motion. Thus current is carried to the rod which is insulated as are the electrodes. Grounding either completes the circuit. Actually the contact between an arm released by its selvage thread completes a circuit to set certain stop motion mechanism in action for stopping the loom, said circuit preferably being completed through ground since the arm 25 is grounded through its disk and attendant mechanism to the frame of the loom, current passing through the electrodes 35, lead 36 and rod 33 to the released arm 24 or 25 as the case may be all in a manner presently to be described by reference to the diagrammatic Figure 7.

Referring to Fig. 7, one stop motion circuit which may be employed has been diagrammatically illustrated and the manner in which the selvage thread stop mechanism is adapted to function therewith is graphically shown. According to the broader concept of the invention, the selvage thread stopping means may be employed either as an independent stop mechanism or in conjunction with those stopping means already provided on the loom. Of course, the latter is more preferable in that less mechanism is involved and the existing circuits serve very well without the addition of any appreciable number of added parts. The particular circuit herein shown is described in greater detail in copending application Serial No. 336,280, filed February 11, 1953, now Patent No. 2,707,977. In 75

that circuit which is essentially a direct current one, alternating current is provided, preferably as transformed, ungrounded 12-volt source and is rectified by any convenient means such as the full wave, selenium type rectifier 38 the output of which is passed through a feed line 39 in which is a resistance 40, the current then being branched to a power stop and a warp stop means. The power stop mechanism generally indicated by numeral 41 functions in a manner not necessarily to be described here, but through a holding solenoid 42 the coil of which is grounded at 43 and the other branch of which leads to electrodes 35 of the warp stop motion, this current being possible of grounding at 44 whenever a drop wire falls thereby to complete a circuit. The general operation of such warp stop motions is clearly understood and need not be described in detail here.

The added means involving clamp 37, lead 36 and rod 33 is effective to complete the circuit to ground at 45 whenever one of the arms 24 or 25 is released due to failure of its thread S. Thus it may be seen that the stop motion herein described and claimed and effective upon the selvage threads only, functions through the available stop motion circuit to stop the loom and thereby obviates any possibility of the loom's continuing to run to weave fabric without a properly formed selvage.

While the description to this point has merely dealt with the stopping function incidental to the parts, the spring urged arms 24 and 25 exert a continuous tensioning force on the selvage threads S and always maintain them in taut condition. This tensioning force and draw-back action are applied relatively close to the point at which the selvage is formed and have been found to be much more effective than tensioning means only applied back at the source of supply 14 and 15. The result is that more uniform tension conditions apply at the selvage and the actual product resulting is more desirable.

Now referring to Figs. 4 and 5, a modification of the invention has been illustrated wherein the arms pivoted and spring pressed outwardly on the disk 10 have themselves been formed as spring members and are very much lighter than the arms 24 and 25, Fig. 2, thereby reducing the effect of inertia and rendering the device more responsive to tension changes. Forces set up due to the mass of the parts subject to centrifugal force are rendered negligible so that the spring biasing means is accountable for virtually all of the action imparted to these members. Parts which are substantially identical with similar parts of Figs. 1 and 2 have been indicated by like numerals with primes. The disk 10' carries instead of the counterbored bosses 31 mounting bosses 46, Fig. 6, within which are retained shoulder bolts 47 held in place by nuts 48 and about the shanks of which are positioned the coils 49 of the spring-like ends of wire arms 50 and 51 the free ends of which have been looped as shown at 46' for the passage of a selvage thread. These spring arms are actually formed from as fine wire as is practicable to be utilized for the purpose and the inertia thereof is relatively insignificant compared to the force with which they are urged outwardly. Two holder studs 52 and 53 retain a bail or confining wire 54 which is not contacted by either of the arms 50 or 51 during normal operation of the parts, but which does serve to restrain them in the event some unusual forces or action may be experienced. The studs 52 and 53 may also serve as stop means for the spring arms which might otherwise move outwardly and then continue to swing about their pivot to a point where their ends would be shielded by the disk and thus assume a position in which they might not contact the rod 33'.

The rod 33' may be mounted as is rod 33 in the form of the invention disclosed and shown in Figs. 1 and 2. However, it is further contemplated that this contact member or rod 33, also rod 33' of the modification, may be mounted on the casing 12 and current from the electrode or electrodes 35 connected thereto just as in the

construction shown here, the advantage of mounting the rod on the casing 12 being that adjustment of the position of the warp stop motion will then have no effect on the position of the rod. Of course, the rod must be insulated from the support.

According to the forms of the invention disclosed to this point, a contact made at the rod by one of the outwardly biased arms grounds the circuit through the selvage thread mechanism, but it is also contemplated that the grounding of the circuit may be performed by a mechanical means adapted to be tripped by one of the arms when it has been released due to failure of the selvage thread individual to it. Referring to Figs. 8 and 9, the warp stop motion mechanism has mounted thereon a bracket or holder 55 which mounts pivots 56 and 57. At the first of these a wire formed to present two arms one of which is indicated at 58 and the other at 59 projecting from a central coiled part 60 is adapted to be swung on the pivot 56 being urged downwardly by means of a spring 61 to engage current carrying means such as the electrodes 35 of the warp stop motion. However, during normal operation of the mechanism, this two-armed, pivoted contact means is held out of engagement with the said electrodes by means of a detent 62 which is in turn a part of a wire member having a more or less laterally extending arm 63, both the detent and arm being extensions of a central coiled part 64 which is also freely pivotable on pivot 57. The detent tends to be maintained in position by spring 65 which is attached to the detent 62 at a central offset part thereof and normally holds the laterally extending wire member 63 in its horizontal position, that is, in a position in which its laterally bent end 66 thereof will be contacted by one of the arms of the selvage thread stop motion when the latter is biased outwardly as above described.

In operation, this contacting means is normally set manually as illustrated in these Figures 8 and 9, but is released when one of the stop motion arms engages the outer end 66 of arm 63 thereby disengaging the detent from arm 59 whereupon spring 61 quickly draws the contact member 58 downwardly onto the electrodes of the warp stop motion grounding the stop motion circuit through the bracket 55 and the frame of the loom. Thus it is not necessary to provide a ground through the selvage thread feeding means, although that is not particularly difficult, but this last mentioned system does function rather more directly to ground the current and thereby to complete the circuit for initiating the stopping action. It may also be mounted on the casing 12 rather than on the warp stop motion.

This description has so far dealt with electric stopping means, but, of course, the indication for stopping may become effective through a mechanical stop motion such as the warp stop motion of U. S. Patent 1,924,790 or others. In that event, the wire arm 58 may fall into the teeth of the sliding bars of the stop means and then, in a known manner, may cause stopping of the loom.

While one embodiment of the invention and modifications have been disclosed, it is to be understood that the inventive concept may be carried out in a number of ways. This invention is, therefore, not to be limited to the precise details described, but is intended to embrace all variations and modifications thereof falling within the spirit of the invention and the scope of the claims.

I claim:

1. In a selvage thread shedding and twisting means for looms which includes a rotating member cooperating with a thread feeding means rotating with said member to prevent twisting of the thread between the member and feeding means, loom stopping means and other means rotatable with said member and feeding means and under control of the selvage threads for actuating said loom stopping means upon failure of a selvage thread.

2. In a selvage thread shedding and twisting means for looms which includes a rotating member cooperating with a thread feeding means rotating with said member to prevent twisting of the thread between the member and feeding means, loom stopping means and other means carried by and rotatable with said member and under the control of the selvage threads for actuating said loom stopping means upon failure of a selvage thread.

3. In a selvage thread shedding and twisting means for looms which includes a rotating member cooperating with a thread feeding means rotating with said member to prevent twisting of the thread between the member and feeding means, loom stopping means and means continuously effective for independently sensing the condition of each of the selvage threads for actuating the loom stopping means upon an abnormality in a selvage thread.

4. In a selvage thread shedding and twisting means for looms which includes a rotating member cooperating with a thread feeding means rotating with said member to prevent twisting of the thread between the member and feeding means, loom stopping means and other means carried by said member, the position of which means is controlled by a selvage thread individual thereto, said other means being effective upon failure of its selvage thread for actuating said loom stopping means.

5. In a selvage thread shedding and twisting means for looms which includes a rotating member cooperating with a thread feeding means rotating with said member to prevent twisting of the thread between the member and feeding means, loom stopping means and other means comprising spring urged, pivoted means carried by said member and through which a selvage thread is threaded for actuating said loom stopping means upon failure of a selvage thread.

6. In a selvage thread shedding and twisting means for looms which includes a rotating member cooperating with a thread feeding means rotating with said member to prevent twisting of the thread between the member and feeding means, loom stopping means which includes a circuit completing contact member, and means rotatable with said rotating member and feeding means and normally maintained in position by a selvage thread individual thereto by movable to a position to engage said circuit completing contact member upon failure of a selvage thread.

7. In a selvage thread shedding and twisting means for looms which includes a rotating member cooperating with a thread feeding means rotating with said member to prevent twisting of the thread between the member and feeding means, loom stopping means which includes a circuit completing contact member, and means rotatable with said rotating member and under the control of a selvage thread movable upon failure of such thread for grounding said member.

8. In a selvage thread shedding and twisting means for looms which includes a rotating member cooperating with a thread feeding means rotating with said member to prevent twisting of the thread between the member and feeding means, loom stopping means which includes a circuit completing contact member and means for grounding said member which comprises a spring biased arm pivoted to said rotating member and through the free end of which a selvage thread is threaded, said arm normally being held in restrained position by its thread, but being movable upon failure of that thread to extend radially outward of the rotating member and to make contact with said contact member.

9. In a selvage thread shedding and twisting means for looms which includes a rotating disk cooperating with a thread feeding means rotating with said disk to prevent twisting of the thread between the disk and feeding means, a loom warp stop motion and means functioning to stop said loom upon failure of a selvage thread

which comprises a circuit completing member forming a part of said warp stop motion and means for grounding said member which comprises a spring biased arm pivoted to said rotating member and through the free end of which a selvage thread is threaded, said arm normally being held in restrained position by its thread, but being movable upon failure of that thread to extend radially outward of the rotating member and to make contact with said contact member.

10. In a selvage thread shedding and twisting means for looms which includes a rotating member cooperating with a thread feeding means rotating with said member to prevent twisting of the thread between the member and feeding means, a loom warp stop motion and means for stopping the loom on failure of a selvage thread and 15

for maintaining a uniform tension in those threads as they are incorporated in a fabric selvage which includes spring biased arms pivoted at said rotating member and having looped ends through which the selvage threads are passed.

11. Mechanism as in claim 10 wherein said arms are formed of spring wire thereby to reduce the mass of parts subject to centrifugal forces as they are moved with the rotating member to which they are pivoted.
